UNITED STATES PATENT OFFICE.

ORLOFF HENRY, OF NEW ORLEANS, LOUISIANA, ASSIGNOR TO THE PI KAPPA ALPHA FRATERNITY, OF ATLANTA, GEORGIA, A LIMITED PARTNERSHIP.

DESIGN FOR A FRATERNITY PIN OR BADGE.

56,156.

Specification for Design.

Patented Aug. 24, 1920.

Application filed June 14, 1920. Serial No. 389,025. Term of patent 14 years.

To all whom it may concern:

Be it known that I, ORLOFF HENRY, a citizen of the United States, residing at New Orleans, in the parish of Orleans and State of Louisiana, have invented a new, original, and ornamental Design for a Fraternity Pin or Badge, of which the following is a specification, reference being had to the accompanying drawings, forming a part thereof.

The figure is a front elevation of a fraternity pin or badge showing my new and ornamental design.

I claim:

The ornamental design for a fraternity pin or badge as shown.

In testimony whereof I affix my signature.

ORLOFF HENRY.
